UNITED STATES PATENT OFFICE.

HORACE JOHN WEEKS, OF CHRISTCHURCH, NEW ZEALAND.

STOP FOR WINDOWS OR DOORS.

SPECIFICATION forming part of Letters Patent No. 783,659, dated February 28, 1905.

Application filed September 14, 1903. Serial No. 173,162.

To all whom it may concern:

Be it known that I, HORACE JOHN WEEKS, a subject of His Majesty the King of Great Britain and Ireland, residing in Manchester 5 street, Christchurch, in the Provincial District of Canterbury, in the Colony of New Zealand, have invented a new and useful Stop for Windows or Doors, of which the following is a specification.

10 This invention provides a cheap and effective device whereby a window or door to which it is applied may be secured against opening from the outside beyond a predetermined limit.

15 Referring to the drawings, which form a part of this specification, Figure 1 is an inside elevation of a sash-window; Fig. 2, a front perspective elevation showing the stop closed; Fig. 3, a similar view showing the 20 stop open, and Fig. 4 is a side sectional elevation.

The same numerals indicate the same parts throughout the figures.

The bracket 1 is disk-shaped, so that it may 25 be readily fitted into a circular hole formed by an ordinary boring-bit in the window-sash 2, the face of the bracket being flush with the surface of the sash. Holes 3 receive wood-screws 4, by which the bracket is secured.

30 A catch-lever 5 fits within a diametrical recess 6 in the bracket and is pivoted therein near its edge at one end upon a pivot-pin 7. A flat spring 8 within the recess and held in position by a rivet 9 bears against the under 35 side of the pivoted end of the catch. The forward end of the catch is beveled to permit a finger to be passed beneath it to turn it upon its pivot.

When it is desired to prevent the window from being opened from the outside, the catch 40 is turned upon its pivot into the position shown in Figs. 1 and 3 and in dotted lines in Fig. 4. The point at which the catch is pivoted prevents it from turning after the catch is at right angles to the bracket, and when attempt is made to open the window the lower sash contacts with the catch.

When applied to a door, the bracket is sunk in the floor, and when the catch is raised the lower edge of the door contacts with it and 45 prevents the door from opening farther.

Having now described my invention, what I claim as new, and desire to secure by Letters Patent, is—

For the purpose indicated in combination a 55 disk-shaped bracket having holes to receive screws by which it is held in position, and a diametrical recess, a catch-lever fitting said recess and pivoted therein, the forward end of said catch-lever being beveled, and the pivot 60 arranged so that said catch is prevented from turning beyond a right angle to the bracket, and a flat spring secured within the recess adapted to maintain the catch in position when turned upon its pivot at right angles to 65 the bracket substantially as set forth and illustrated.

In witness whereof I have hereunto set my hand in presence of two witnesses.

HORACE JOHN WEEKS.
